GARMENT FOR FEMININE WEAR

Marian Halstead, New York, N. Y.

Application August 24, 1954, Serial No. 451,891

4 Claims. (Cl. 2—30)

2

Figure 4 is a view, in side elevation, of a garment embodying the features of the instant invention and showing the flap seat in open position and a halter strap bra;

Figure 5 is an exploded view of the garment specifically illustrated in Figures 1 and 2, showing the contour and cut of the individual pieces of fabric which are joined together in the production of the garment;

Figure 6 is a front elevational view showing the individual pieces, as shown in Figure 5, in fully assembled relationship ready to be worn;

Figures 7, 8 and 9 are front side views illustrating variations of the basic garment construction as shown in Figures 1 through 6 especially suited for beachwear use;

Figure 10 is a front elevational view of a further modified form of the invention supportable independently of an attached bra;

Figure 11 is a view in side elevation of the garment modification of Figure 10 showing the flap seat in open position;

Figure 12 is an exploded view of the garment modification of Figures 10 and 11 showing the contour and cut of the individual pieces of fabric which are joined in the production of the garment, and

Figure 13 is a front side view of a modified form of the garment incorporating the figure control features of the instant invention and ideally suited for use in the support of stockings.

For the most effective description of the various pieces of fabric which are united to make up the garment of the instant invention, reference will first be had to Figures 5 and 6 which respectively illustrate an exploded view and an assembled view of the individual fabric pieces. In the embodiment illustrated in these figures, a front abdominal panel 10 is provided to cover the lower abdominal region of the wearer, such panel having a convexly curved upper edge 11 joined to the concavely curved lower edge 12 of a lower chest bridging panel 13 to provide a seam curving upwardly adjacent the mid-point thereof. This seam, when the garment is positioned on the wearer, extends generally across the waist and slightly above the stomach so as to preclude cutting of the garment seam into the flesh at the waist. Thus restriction of the wearer's breathing is alleviated while permitting expansion of the flexible area of the diaphragm.

The edges along the sides of the abdominal panel 10 and chest bridging panel 13, when these two panels are joined at their edges 11 and 12, flare outwardly along lines 14 and 15 from the upper edge of the chest bridging panel to a point of maximum transverse dimension for the abdominal panel 10. A pair of side panels 16 and 17 are joined along their respective edges 18 and 19 to the side flaring edge lines 14 and 15 made up by the abdominal panel 10 and chest bridging panel 13. The side panels 16 and 17 are of such a length that their respective edges 18 and 19, which are joined along lines 14 and 15, terminate at the upper edge of the chest bridging panel 13 and the point of maximum transverse dimension of the abdominal panel 10.

Below the point of maximum transverse dimension of front abdominal panel 10, such panel tapers in width along a pair of concavely curved lines 20 and 21, which lines are the garment edges which pass across the hips and downwardly above the upper part of the thighs toward the crotch of the wearer when in use. From the lower ends of the concavely curved lines 20 and 21, the abdominal panel 10 narrows along a pair of converging concavely curved lines 22 and 23, terminating at the ends of lines 22 and 23 in a generally semi-circular lower edge 24 to be joined with a crotch section 25.

Referring again to the side panels 16 and 17, it will

This invention relates to a garment for feminine wear. Such garment, as hereinafter specifically disclosed, is especially well suited for feminine figures requiring a minimum of figure control and permits maximum freedom of bodily movements without adversely affecting the form fitting, non-wrinkling contour of the garment on the wearer. More specifically, the invention incorporates lightness of construction in a woman's garment with comfortable body control and smooth fitting lines to enhance posture and figure appearance.

It is a specific object of this invention to provide an extremely light-weight garment for feminine wear having a waist encircling portion contoured to fit smoothly over the hips of the wearer without cutting and further having a bust supporting portion associated with the waist encircling portion so constructed and designed as to permit maximum freedom of body movement while retaining smoothness of fit of the garment over the anatomy and comfortable control of the body curves, such garment being well suited for use with stocking supporting, if desired.

It is further object of this invention to provide a garment having a form fitting waist encircling portion passing above the hips without cutting into the flesh and muscle tissue associated therewith and including a crotch portion and sectionalized rear flap seat with the crotch portion so constructed and designed in its juncture with the waist encircling portion and the flap seat as to alleviate cutting of the leg tendons of the wearer and thus promote comfort and bodily freedom of movement for the wearer whether or not the garment is used for stocking support.

It is an additional object of this invention to provide a feminine garment offering extreme snugness of fit for improved figure appearance and posture, such garment having a waist encircling portion and bust supporting portion interrelated to insure bosom uplift and support action, and also having an improved crotch structure carrying a rear flap seat so designed as to alleviate leg tendon cutting.

Still further objects and purposes of the invention reside in the provision of a garment suitable for low cost mass production and offering to the wearer comfortable control of body curves and smooth, non-wrinkling contour fitting without cutting into the anatomy at any of the seams or edges of the garment.

Other objects and advantages of the instant invention will be readily apparent from the specific description set forth hereinafter, taken in connection with the accompanying drawings in which:

Figure 1 is a view of a garment according to one modification of the invention showing a rear side view thereof as it appears on the wearer;

Figure 2 is a front side view of the garment as shown in Figure 1;

Figure 3 is a rear side view of a garment similar to that shown in Figures 1 and 2, as especially designed for beachwear;

be observed that such panels, in position on the wearer, extend rearwardly around the sides of the body under the arms and back of the chest cage to be joined by suitable fastening means 30 and 31 secured to the outer free ends of the side panels. These fastening means cooperate with each other adjacent the small of the back to position the garment in encircling relation to the wearer's waist. The lower edges 32 and 33 of the respective side panels 16 and 17, when such panels are joined to the abdominal panel and lower chest bridging panel, form continuations of the respective concavely curved lines 20 and 21 of the abdominal panel 10. Such edges 32 and 33 and lines 20 and 21 extend from the point of connection of the fastening means 30 and 31 at the small of the back of the wearer around, over and above the hips of the wearer, across the upper part of the thighs and downwardly toward the crotch. These curved edges of the garment must smoothly engage and comfortably fit across the hips of the wearer to insure against wrinkling of the fabric of the garment and uncomfortable cutting of the garment edges into the wearer's anatomy.

As shown more clearly in Figure 4, the seam line 14 terminates immediately above the hip bone at the junction of edge 33 and line 21. To insure smooth, non-wrinkling and non-cutting fit of the garment across this portion of the anatomy, a fabric fullness is provided at 35 for proper desired fit of the garment edge across the hip bone and muscle tissue associated therewith.

As illustrated in Figures 5 and 6, fabric fullness at 34 and 35, which respectively engage over the opposite hip bones of the wearer, is provided in the instant invention by the particular cut of the edges of abdominal panel 10 adjacent its point of maximum transverse dimension in relation to the cut of side panels 16 and 17 adjacent their lower edges 32 and 33. It will thus be apparent that as these panels are joined along the lines 14 and 15, the edges 32 and 33, as continuations respectively of lines 20 and 21, will have imparted adjacent their junction with such lines a fabric fullness at 34 and 35. This fullness permits the garment to smoothly and snugly engage across the hip muscle tissue which is associated with the terminus of the hip bone.

Although in the embodiment illustrated, the fabric fullness at 34 and 35 has been provided by the specific cut of the panels 10, 16 and 17, it will be appreciated that within the scope of the instant invention such fabric fullness might be imparted to the garment at this particular location by a separate piece of fabric inserted at the junction of the seam with the body engaging edges of the garment or by other suitable equivalent means.

Returning to the lower chest bridging panel 13, it will be observed that the upper edge thereof has a central upstanding portion 40 forming on the opposite sides thereof breast cup receiving cut-outs 41 and 42. The upstanding portion 40 is slightly tapered so that the side edges thereof, which form a part of the cut-outs 41 and 42, are straight and almost vertical. These side edges curve sharply outward from the base of upstanding portion 40 into the almost horizontal upper edge of the panel 13 to complete the breast cup cut-outs 41 and 42. Cut-outs 41 and 42, together with the upper edges 43 and 44 of the respective side panels 16 and 17, form the seam line to be joined to the breast cup sections. The form of the openings for the breast cups, together with the sectionalized breast cup structure as described hereinbelow has been found to materially contribute to bust support and uplift in the complete garment structure.

The breast cups, for connection to the upper edge of chest bridging panel 13 and side panels 16 and 17, are each formed of an upper section 45 and a lower section 46. The lower sections 46 each have an edge which is sewn to one of the cut-outs 41 or 42 and an opposite edge which is joined with a mating edge of the appropriate upper section 45 to produce breast cup seam lines 47 and 48 (see Figure 6). The breast cup seam lines

47 and 48 extend outwardly, generally horizontal, with a slight rise from the side edges of upstanding portion 40 to the apex or tip of the breast cup. Thereafter the seam lines curve downwardly at an angle to the vertical to join with the ends of lines 14 and 15 formed by the side edges of panels 10 and 13.

In the construction of the garment of the instant invention, a structure has been achieved which insures maximum comfort and freedom of body movement to the individual wearer while still retaining the desired bust uplift and support to enhance posture and figure appearance. It has been found that the particular bust cup construction and breast cup cut-out form, as hereinabove described in combination with the other elements of the garment, insures the required breast support and uplift even in the absence of shoulder straps being used with the garment. In the absence of such straps, stiffening may be applied as desired to provide desired breast cup form. Thus, the sectional breast cups with two sections united along a seam line disposed as lines 47 and 48, so as to extend outwardly from the center line of the garment substantially horizontal, with a slight rise to the tip of the breast and thence across the tip, turning gradually downwardly at about a sixty degree angle to the horizontal and terminating beneath the heavy portion of the breast, has been found to give the desired results in the completed garment. Accordingly, as clearly illustrated by several of the views on the drawings showing the garment positioned on the wearer, the seam line for the breast cups does not terminate vertically beneath the breast but joins with the lines 14 and 15 in the garment structure at the outer underside of the respective breasts.

A pair of shoulder straps 49 extending over the shoulders are provided connected between the uppermost point on the upper sections 45 of the breast cups and the edges of the side panels 16 and 17. These edges, as is apparent from the description hereinabove, extend rearwardly around the sides beneath the arms of the wearer.

Referring more specifically to the crotch section 25, it will be noted that the section flares outwardly along a pair of concavely curved lines 50 and 51 from a generally semi-circular end edge 52, which is united with the lower edge 24 of abdominal panel 10, to a convexly curved end edge 53. The end edge 53 is united with the flap seat of the garment which is made up of a pair of seat panels 54 and 55, which panels are joined along a center seam 56 to provide the flap seat for the garment. The opposite edges of the flap seat are curved outwardly along lines 57 and 58 which, as continuations of the edges 50 and 51 of crotch section 25, extend upwardly to snugly engage beneath the buttocks of the wearer. The flap seat narrows in width from its point of maximum transverse dimension along a pair of converging straight lines 59 and 60, the ends of which lines are joined by a curved line 61 which, on the wearer, forms the top edge of the flap seat. The sectionalized flap seat and its connection with the curved end edge 53 gives control to the fit of the seat so that it smoothly and snugly engages across the cheeks of the buttocks of the wearer and at the crease between the legs and buttocks.

Fastening means 62 are provided to cooperate with fasteners 63 carried by the front abdominal panel 10 on the opposite sides thereof. Similar suitable fastening means 64 are provided at the opposite ends of lines 59 and 60 of the flap seat to cooperate with fasteners 65 also carried by the abdominal panel 10. Intermediate the fasteners 62 and 64, along edge lines 59 and 60, there may be provided additional fastening means 66 which cooperate with spaced fasteners 67 carried by the front abdominal panel 10.

As shown, a series of laterally spaced fasteners are provided on abdominal panel 10. It is generally desirable that some such fastening means be provided on the gar-

ment since this enables adjustment of the garment to accommodate different figure variations in the anatomy of the persons using the garment, without alteration of the garment.

Again referring to the crotch section 25, specific attention is directed to the connection thereof with the lower end of abdominal panel 10. As described hereinabove, the generally semi-circular edges 24 and 52 are joined to unite the crotch section 25 with panel 10. The formation of the edges by reason of the cut of these two garment pieces results in a formed crotch structure wherein the edges of the material 22 and 50 on one side thereof and 23 and 51 on the other side do not cut into the leg tendons adjacent the forward part of the crotch but instead provide smooth comfortable fit of the crotch with the wearer's anatomy, thus promoting freedom of body movement without encountering cutting of the leg tendons.

The general fit and mode of application of the assembled garment, as shown in Figure 6, to a feminine figure will be generally apparent from the views shown in Figures 1 through 4. From these illustrations it will be apparent how the free ends of the side panels are fastened adjacent the small of the back to retain the abdominal panel, lower chest bridging panel and sectional breast cups in smooth, snugly fitting relation across the front of the figure. Also, these showings illustrate the manner in which the flap seat is connected to the fasteners provided on the front abdominal panel 10.

The appropriate positioning of stocking supporters 70 in relation to the assembled garment is shown on Figure 6 and their position when the garment is being worn, illustrated on Figures 1 and 2. It will be appreciated that such supporters are suitably secured to the garment as by tabs sewn to the panels at the appropriate points along their edges. As desired in use the garment may be worn with or without such stocking supporters.

Figures 3 and 4 illustrate a garment having the same basic characteristics as that illustrated in Figures 1 and 2 and assembled from similar fabric pieces as shown in Figures 5 and 6. However, in these two figures the garment is especially designed for wear as a bathing suit or for general sportswear use. Thus in Figure 3 the leg encircling garment edge of the flap seat, crotch section and abdominal panel is provided with a band or cuff 75 which may be adjustable or elasticized if desired and a decorative strip or cuff 76 sewn along the upper top edge of the garment to enhance the garment's appearance when used for beach or sportswear.

Figure 4 illustrates a slightly different beachwear garment embodying the structural characteristics of the instant invention employing in the place of the straps 49, a halter or removable strap 77 and utilizing tied fastening means, indicated generally at 78, in place of the more usual hook type fasteners which are employed in the garment illustrated in Figures 1 and 2 to fasten the flap seat to the front abdominal panel and the outer ends of the side panels to one another at the small of the back. As in the case of Figure 3, the leg engaging edges of the garment of Figure 4 are provided with an inelastic band or cuff 75 which may be adjustable or elasticized, if desired, and a decorative strip 76 applied across the top edge of the garment to give an attractive appearance to the garment for beachwear use. It will also be noted that with the use of a halter strap 77 in place of the shoulder straps or when no shoulder straps are employed, the edge line of the side panels may be altered to do away with the sharp bend as illustrated in Figures 1, 5 and 6. Accordingly, as shown at 79, the line extending downwardly and rearwardly from the point of connection of the shoulder strap 77 to the tie fasteners at the back of the garment may take a generally concave and then convex curve to smoothly engage around the side lower portion of the chest cage and beneath the arm of the wearer.

Further reference may be had to Figure 4 as illustrating 75 with the convexly curved end of the crotch section 92

the positioning of the edge line 21 of abdominal panel 10 and edge 33 of side panel 17. This figure thus shows the location of the fabric fullness 35 which insures smooth and snug engagement of the garment as it passes over 5 above the hips, around the side of the wearer to the back to be secured to the other side of the garment.

Briefly referring to Figures 7, 8, and 9, such views illustrate various modifications of the basic garment structure for beachwear use. Thus Figure 7 suggests a flaring 10 skirt 80 sewn to the basic garment structure along the upper edge of the chest bridging panel along the seam beneath the bust cups and also sewn to the diagonally extending side seams which extend from the underside edge of the bust cups, downwardly and rearwardly along 15 the garment. Figure 8 illustrates the garment with an apron-like skirt 81 secured across the front of the garment and Figure 9 illustrates the basic garment structure having a waist encircling belt 82 used in conjunction with the basic garment. It may be noted that in garments incorporating the novel features of the invention, made of a fabric having a design, such as a plaid, stripes or other pattern, a center seam may be provided extending through the lower chest bridging panel, abdominal panel and crotch to facilitate matching of the fabric pattern or design. Also, within the scope of the invention, the upper breast cup section could be formed of fabric pieces seamed to give attractive fabric pattern matching.

Referring to the modification shown in Figures 10, 11 and 12, which modification is adapted to be worn independently of an affixed bra, it will be observed that the front abdominal panel 88 corresponds generally to the cut and contour of the abdominal panel 10 of the modification of Figures 1 through 6. However, the upper edge of 20 abdominal panel 88 is formed with a concavely curved 25 line 89. This line provides a dip at the center front of the garment so that, as positioned on the wearer, the fabric edge does not tend to cut into the wearer's stomach so as to be uncomfortable but instead rides slightly beneath the waistline insuring a smooth, non-wrinkling fit across the front of the garment. A pair of side members 30 90 are seamed to the side edges of the abdominal panel 88 and are provided at their outer free ends with cooperating 35 fastening means 91 which are adapted to be interconnected at the small of the back to position the garment 40 in waist encircling relation to the wearer.

As illustrated in the drawings, the cut and contour of the fabric pieces 88 and 90 are so related as to provide a fullness in the garment edge line which passes over the hip 50 similar to the fabric fullness provided at 34 and 35 as illustrated on Figure 6. Thus, a smooth, non-wrinkling and non-cutting engagement of the garment material across the 55 hips of the wearer is insured. Further along the upper edge 89 and the upper edges of side members 90, material is provided by the cut and contour of such fabric pieces so as to provide a non-cutting edge which edge extends up just beneath the wearer's chest cage so that the flesh lies encased in and beneath the fabric pieces rather than rolling out and over the edge as would be characteristic of an 60 edge not possessing the fullness at this point in the garment. Although the desired garment edge fullness has been provided in the illustrated embodiment by the cut and contour of the individual fabric pieces, it will be readily recognized that within the scope of the instant invention, such edge fullness may be appropriately provided by insertion of a gusset or extra fabric piece instead of by the cut of the fabric pieces 88 and 90.

A crotch section 92 is secured to the lower edge of the abdominal panel 88 and is formed similarly to the crotch section 25 described hereinabove with regard to Figures 5 and 6. A flap seat, made up of seat panels 93 and 94, is secured to the convexly curved end of crotch section 92 and the two seat panels 93 and 94 sewn together along a center seam. The sectionalized flap seat in conjunction 70 75 with the convexly curved end of the crotch section 92

gives effective control of the seat fit so that the flap seat smoothly and snugly engages upwardly beneath the buttocks of the wearer.

Particular attention is called to the form of the leg engaging lines 95 and 96 of the flap seat shown in Figure 12 in comparison with the leg engaging lines 57 and 58 of the flap seat illustrated in Figures 5 and 6. The curvature of lines 57 and 58 provides a seat fullness particularly desirable for formation of a garment for use as an undergarment, particularly where it is contemplated that such garment will be used for the supporting of stockings. Thus, when the garment is used with stocking supporters, the pull of the stockings on the wearer insures that the leg engaging edge lines 57 and 58 of the respective flap seat panels will be retained snugly down at the crease between the legs and the buttocks. In a structure such as illustrated in Figure 12, the leg engaging lines 95 and 96 do not possess the same fullness as lines 57 and 58 since it has been found that with a tight inelastic band as might be employed in a bathing suit or other sport wear garment, a cut for the flap set such as illustrated in Figure 12 is desirable.

Figure 12 also illustrates a further edge line change in the cut of the flap seat in that it will be noted that the lines 97 and 98, which are secured to the front abdominal panel, are not straight as in the case of similar lines 59 and 60 of the garment of Figures 5 and 6. Instead, in Figure 12, these lines are curved toward the concave line 99 which line extends across the back of the wearer when the garment is in use. A slight curvature in the cut of lines 97 and 98 is desirably provided where it is contemplated that the edges will be sewn to the front of the abdominal panel. It has been found that this curvature, coupled with sewing of the flap seat edges to the abdominal panel along straight, generally vertical parallel lines results in better abdominal fit of the garment on the average wearer. With the flap seat edges sewn to the abdominal panel, the center seam of the rear flap seat may be openable through provision of suitable fastening means to facilitate applying and removing the garment. Of course, where detachable fasteners are used, figure variations between individual wearers may be readily accommodated by utilizing different ones of the fasteners mounted on the front of the abdominal panel.

Although variations of the cut and contour of the flap have been specifically illustrated with respect to the embodiment of Figure 12, it is to be understood that such variations are equally applicable to the embodiment described hereinabove. Thus, where the garment of Figures 5 and 6 is to be used as a bathing suit with an inelastic band along edges 57 and 58, such edges preferably will be cut and contoured similarly to the lines 95 and 96 in Figure 12. Also where the flap seat edges are to be sewn to the abdominal panel 10, such edges will be cut and contoured such as shown at 97 and 98 in Figure 12.

In Figure 13 there is shown a garment embodying features of the instant invention which is ideally suited for stocking support in conjunction with desired body contour control and bust uplift. This garment is characterized by several of the fabric pieces thereof being similar to the various elements described with regard to Figures 5 and 6. Accordingly, similar reference numerals are applied to this figure where they have a counterpart in the embodiment of Figures 5 and 6. In the embodiment of Figure 13 a front abdominal panel 85 is joined with the lower edge of the lower chest bridging panel 13 and side panels, similar to the structure illustrated in Figures 5 and 6. However, in this embodiment the lower edge of panel 85 is not connected to a crotch section, such crotch section being omitted. Accordingly, the abdominal panel 85 hangs downwardly on the wearer fitting snugly across the abdomen to the end of the torso. Suitable stocking supporters 86 are carried at appropriate points at the lower edge of the abdominal panel 85.

The form of the invention illustrated in Figure 13 offers a maximum of freedom of bodily movement to the wearer together with extreme comfort while offering stocking support and bust, waist and abdomen control. 5 It will be readily recognized that the basic advantageous characteristics of the elements as described hereinabove with regard to Figures 5 and 6 are similarly present in the garment shown at Figure 13. Thus, the smooth, non-wrinkling and non-cutting fit of the garment across the 10 hips, extending from the fabric fullness at 34 and 35 (Figure 6), is likewise carried over into the construction of the garment in Figure 13. Further, the improved bust cup structure, co-acting with the rest of the garment structure, results in firm but comfortable breast support 15 to the wearer of the garment. In this regard it is again to be noted that the bust cup seams terminate at a point laterally of the underside of the breast to transfer maximum lift to the heaviest portion of the bust along the seam lines extending rearwardly and downwardly toward 20 the hips of the wearer.

Reference will now be made to a preferred cut of the 25 separate fabric pieces, i. e., as to whether such pieces are cut on the bias or on the straight. This relationship between the cut of the various fabric pieces has been 25 found to result in a finished garment having ideal fit on female anatomy to conform to the curves thereof and impart comfortable figure control and support without wrinkling or cutting of the material edges into the 30 wearer's anatomy.

35 In the preferred construction, the front abdominal panel is cut on the straight with the warp extending transversely across the width of the fabric. The lower chest bridging panel is cut on the bias if of woven or elasticized material to offer smooth, even fit of this panel across the lower chest cavity beneath the bust of the wearer. The side panels are cut substantially on the bias with the warp of the material of such panels transferring tension forces to the upper and lower portions 40 of the seam lines 14 and 15 where the side panels are joined to the edges of the abdominal panel 10 and lower chest bridging panel 13.

Further, the sections 45 and 46 of the breast cups are 45 cut from the material so that the warp threads therein are directed in lines extending generally between the junction of the breast cup seams with the lines 14 and 15 and the point of attachment of the shoulder straps with 50 respect to section 45 and somewhat parallel to the outer edge of curve 41 with respect to section 46. The crotch section 25 may be cut either on the bias or on the straight and the panels of the flap seat are cut generally on the bias to insure figure fit and snug engagement of the seat 55 beneath and over the buttocks of the wearer.

It will be appreciated that the reference to the specific 60 cut of the material in relation to each of the individual pieces of fabric utilized in making up the garment is given merely as a preferred construction of the garment. However, within the scope of the instant invention, under certain conditions and figure variations, the cut of the various fabric or elasticized material pieces may be altered.

Having thus described my invention, what I claim is:

1. A garment for feminine wear comprising a front abdominal panel, a lower chest bridging panel, said abdominal panel and lower chest bridging panel being joined along their respective upper and lower edges, the edges along the sides of said abdominal panel and said chest bridging panel flaring outwardly from the upper edge of said chest bridging panel to the point of maximum transverse dimension of said abdominal panel, a pair of side panels secured to said side edges respectively, said front abdominal panel tapering in width along a pair of concavely curved lines below said point of maximum transverse dimension and the lower edges of said side panels forming outward continuations of said concavely curved lines, the junctures of said side panels with

the side edges of said abdominal panel having a fullness of material immediately adjacent said concavely curved lines to insure snug, non-cutting engagement of said lines across the hips and rearwardly around the back of a wearer, cooperating fastening means secured to the outer free end portions of said side panels for securing the garment about the waist of a wearer, the upper edge of said lower chest bridging panel having a central upstanding portion forming with the remainder of said upper edge a pair of similarly formed breast cup receiving cut-outs, a pair of breast cups each having an upper section and a lower section, said lower section being joined along one edge thereof to the edge of one of said cut-outs, the opposite edge of said lower section being united with one edge of said upper section to form a seam extending generally horizontally from the side edge of said central upstanding portion outwardly to the apex of the breast cup and thence curving downwardly and laterally to the intersection of the side edge and upper edge of said lower chest bridging panel, and said upper section having an edge joined with the upper edge of the adjacent side panel.

2. A garment for feminine wear as recited in claim 1 wherein the upper edge of said abdominal panel is convexly curved and the lower edge of said chest bridging panel is concavely curved so that the seam formed by joining such edges will curve upwardly adjacent the midpoint of its length to pass above the stomach of a wearer in use.

3. A garment for feminine wear comprising a front abdominal panel, a lower chest bridging panel, said abdominal panel and lower chest bridging panel being joined along their respective upper and lower edges, the edges along the sides of said abdominal panel and said chest bridging panel flaring outwardly from the upper edge of said chest bridging panel to the point of maximum transverse dimension of said abdominal panel, a pair of side panels secured to said side edges respectively, said front abdominal panel tapering in width along a pair of concavely curved lines below said point of maximum transverse dimension and the lower edges of said side panels forming outward continuations of said concavely curved lines, the junctures of said side panels with the side edges of said abdominal panel having a fullness of material immediately adjacent said concavely curved lines to insure snug, non-cutting engagement of said lines across the hips and rearwardly around the back of a wearer, cooperating fastening means secured to the outer free end portions of said side panels for securing the garment about the waist of a wearer, the upper edge of said lower chest bridging panel having a central upstanding portion forming with the remainder of said upper edge a pair of similarly formed breast cup receiving cut-outs, each of said cut-outs having an edge configuration formed with a generally horizontal line portion and a substantially vertical line portion joined at their adjacent ends with an interconnecting concavely curved line, a pair of breast cups each having an upper section and a lower section, said lower section being joined along one edge thereof to the edge of one of said cut-outs with the ends of said one lower section edge terminating at the upper end of the side edge of said central upstanding portion and at the upper end of the side edge of said lower chest bridging panel, the opposite edge of said lower section being united with one

edge of said upper section to form a seam line extending generally horizontally from the side edge of said central upstanding portion outwardly to the apex of the breast cup and thence curving downwardly and laterally to the intersection of the side edge and upper edge of said lower chest bridging panel, and said upper section having an edge joined with the upper edge of the adjacent side panel.

4. A garment for feminine wear comprising a front abdominal panel, a lower chest bridging panel, said abdominal panel and lower chest bridging panel being joined along their respective upper and lower edges, the edges along the sides of said abdominal panel and said chest bridging panel flaring outwardly from the upper edge of said chest bridging panel to the point of maximum transverse dimension of said abdominal panel, a pair of side panels secured to said side edges respectively, said front abdominal panel tapering in width along a pair of concavely curved lines below said point of maximum transverse dimension and the lower edges of said side panels forming outward continuations of said concavely curved lines, the junctures of said side panels with the side edges of said abdominal panel having a fullness of material immediately adjacent said concavely curved lines to insure snug non-cutting engagement of said lines across the hips and rearwardly around the back of a wearer, cooperating fastening means secured to the outer free end portions of said side panels for securing the garment about the waist of a wearer, the upper edge of said lower chest bridging panel having a central upstanding portion forming with the remainder of said upper edge a pair of similarly formed breast cup receiving cut-outs, a pair of breast cups each having an upper section and a lower section, said lower section being joined along one edge thereof to the edge of one of said cut-outs, the opposite edge of said lower section being united with one edge of said upper section to form a seam line extending generally horizontally from the side edge of said central upstanding portion outwardly to the apex of the breast cup and thence curving downwardly and laterally to the intersection of the side edge and upper edge of said lower chest bridging panel, and said upper section having an edge joined with the upper edge of the adjacent side panel, a crotch section having one end joined to the lower edge of said abdominal panel and flaring outwardly from its junction with said abdominal panel, a flap seat secured to the opposite end of said crotch section, said flap seat comprising a pair of similar seat panels joined along adjacent side edges and having convexly curved outward side edges to engage around and beneath the buttocks of a wearer in use, and cooperating fastening means carried respectively by the outer free ends of said seat panels and at laterally spaced positions on said abdominal panels to enable detachably connecting the ends of said seat panels to the abdominal panel in positioning the garment on a wearer.
